UNITED STATES PATENT OFFICE.

SAMUEL CLAIBORNE BAUGHN, JR., OF COMER, KENTUCKY.

NUT-LOCK.

SPECIFICATION forming part of Letters Patent No. 657,507, dated September 11, 1900.

Application filed July 9, 1900. Serial No. 23,039. (No model.)

To all whom it may concern:

Be it known that I, SAMUEL CLAIBORNE BAUGHN, Jr., a citizen of the United States, residing at Comer, in the county of McLean 5 and State of Kentucky, have invented a new and useful Nut-Lock, of which the following is a specification.

This invention relates to nut-locks, and has for its object to provide improved means for 10 attaching a spring-ratchet-locking device to a nut, so that the free end of the ratchet may properly engage with a bolt, to effectively lock the nut against accidental turning thereon and to permit of the convenient removal of 15 the nut.

With this and other objects in view the present invention consists in the combination and arrangement of parts, as will be herein-after more fully described, shown in the accompanying drawings, and particularly pointed out in the appended claims, it being understood that changes in the form, proportion, size, and minor details may be made within the scope of the claims without departing 25 from the spirit or sacrificing any of the advantages of the invention.

In the drawings, Figure 1 is a perspective view of a bolt and nut having a spring ratchet device applied to the latter in accordance 30 with the present invention. Fig. 2 is a front elevation of the bolt and nut. Fig. 3 is an edge elevation of the nut. Fig. 4 is an elevation of the inner face of the nut. Fig. 5 is a transverse sectional view taken on the line 5 5 of Fig. 4. Fig. 6 is a transverse sectional view taken on the line 6 6 of Fig. 4.

Corresponding parts are designated by like characters of reference in all of the figures of the drawings.

Referring to the accompanying drawings, 40 1 designates an ordinary bolt having a plurality of longitudinal grooves 2 formed in the screw-threaded portion thereof. An ordinary nut 3 is fitted to the bolt in the usual manner. One marginal edge of the bolt is provided with a groove 4, which extends transversely across the entire edge, so as to open outwardly at opposite faces of the nut, said groove increasing in width from the inner face to the outer face of the nut. Another groove 5 is formed in the rear or inner

face of the nut and intersects the adjacent inner end of the groove 4.

The ratchet device consists in a substantially L-shaped stiff metal spring 6, which 55 has one arm or branch received within the slot or groove 4, so that the other branch 8 is disposed substantially parallel across the outer face of the nut, with its free extremity bowed, so as to engage with the grooves of the 60 bolt. This ratchet device is formed from a flat piece of spring metal, with the attaching branch 7 comparatively broad to give strength to the device and the other branch being somewhat narrower and bowed to give the 65 required spring action and to bring the free extremity thereof into position for engagement with the grooves of the bolt. The rear extremity of the attaching branch 7 is bent at substantially right angles thereto, as at 9, 70 so as to lie in the groove 5 in the back of the nut and snugly fit said groove, the opposite edges of which are upset, as best indicated at 10 in Fig. 6 of the drawings, so as to overhang and bind upon the portion 9, and thereby 75 fixedly connect the rear end of the ratchet device to the nut. As indicated in Fig. 3, the narrowest portion of the groove 4, which is at the rear end thereof, snugly receives the adjacent portion of the attaching branch, 80 while the remaining portion of the latter is free from the opposite walls of the groove, and thereby may move laterally within the groove, so as to render the spring arm or branch more elastic than if the attaching 85 branch were entirely rigid.

From the foregoing description it will be seen that the present invention provides an exceedingly simple and efficient manner of attaching the ratchet device to the nut without employing separate fastenings, which are liable to become loose. Also the ratchet is flush with the inner face of the nut, and also with the marginal edge thereof, so that it does not present any projections to interfere 90 with the turning of the nut, and the latter may be set up flush against the object to which it may be applied. The spring branch or tongue, which travels across the ratchet-grooves in the bolt, is located entirely upon 100 the outer face of the nut, so as to be in position for conveniently disengaging the free

end thereof from the grooves of the bolt to permit of the removal of the nut.

By reference to Figs. 1 and 2 it will be seen that the bending of the spring-tongue 8 gives a longitudinal twist to the attaching branch 7 of the spring, whereby the outer edge portion of the attaching branch is bent or deflected upwardly or outwardly from the back of the groove, and by pressing inwardly upon the outer extremity of the branch 7 the latter will be twisted in the opposite direction, thereby throwing the extremity of the spring-tongue out of engagement with the groove of the bolt.

15 What is claimed is—

1. The combination with a bolt, having one or more longitudinal grooves formed therein, of a nut fitted thereto, and provided with a groove extending entirely across one edge thereof, and another groove formed in the inner face of the nut and intersecting the inner end of the former groove, and a substantially L-shaped spring ratchet device, having one branch fitted in the first-mentioned groove of the nut, and also bent into the other groove, the walls of the latter being upset against the ratchet device, and the opposite branch of the latter being formed into a spring-tongue located at the outer face of the nut and for engagement with the grooves of the bolt.

2. A nut, having a transverse groove formed entirely across one edge thereof, opening at the front and rear faces of the nut, and increasing in width from the rear face to the front face thereof, and another groove formed in the rear face of the nut and forming a continuation of the former groove, and a substantially L-shaped spring ratchet device, having one branch received within the former groove and out of contact with the opposite

walls thereof, the rear extremity of the branch being bent into the other groove, and the walls of the latter being upset against the bent portion of the branch to fixedly connect the latter to the nut, and said branch having a lateral movement within the former groove, the other branch being formed into a spring-tongue extending across the front face of the nut.

3. A nut, having a substantially L-shaped ratchet-spring, the free branch of which is bowed across the front face of the nut and arranged for engagement with a bolt, the other attaching branch being twisted longitudinally and having its rear end portion secured to one edge of the nut, and the forward portion of the arm being out of engagement with the nut, whereby an inward pressure upon the outer free end of the attaching-arm will twist the latter and throw the free end of the other branch laterally outward.

4. A nut, having a transverse groove formed across one edge thereof, and a substantially L-shaped ratchet-spring having one end bowed laterally across the outer face of the nut for engagement with a bolt, and the other attaching branch having its rear end portion fixedly held between the opposite walls of the groove, the forward portion of the branch being free from said walls and twisted longitudinally, the outer edge portion of said attaching branch being out of contact with the back of the groove.

In testimony that I claim the foregoing as my own I have hereto affixed my signature in the presence of two witnesses.

SAMUEL CLAIBORNE BAUGHN, JR.
